TUNING DEVICE

Filed May 31, 1927

FIG. 1

FIG. 2

FIG. 3

FIG. 4

Inventor
Leopold Muller
By Clemens Bryant Walker

UNITED STATES PATENT OFFICE.

LEOPOLD MULLER, OF SCHONBACH, CZECHOSLOVAKIA.

TUNING DEVICE.

Application filed May 31, 1927, Serial No. 195,518, and in Germany October 6, 1926.

This invention relates to tuning devices of that type consisting of a series of reeds in tubes which are mounted in such manner that any one of them having a reed which units a 5 note of the pitch desired can be selected for use.

In devices of the character described the tubes have been permanently secured to a holder in close or substantially close relation, 10 thereby rendering it difficult to blow into any particular single tube. It is therefore the object of this invention to provide a device of the type referred to of which the tubes containing reeds can be easily separated 15 without destroying the unity of the device.

With the object above referred to in view, the device comprises a series of tubes each containing a reed and hinged to a holder so that the tubes can be rocked about their 20 hinge pins.

Reference being had to the drawings herein:—

Figure 1 is a plan illustrating the device having all the tubes arranged compactly in 25 contiguity.

Figure 2 is a plan of the device illustrating the tubes separated for use.

Figure 3 is a side view of the device showing the tubes separated for use.

30 Figure 4 is a section taken along the line $x-x$ Figure 1.

A series of tubes 1 are each provided at one end with a lug 2 adapted to fit between similar lugs 2^a arranged in series along a 35 holder 3 and to be hinged between said lugs by pins 4.

The holder 3 consists of a suitable length of sheet metal or other material bent into U-formation as shown in Figure 3.

When out of use and, for compact storage, 40 the tubes are folded into the positions shown in Figure 1, but can be readily separated as shown in Figure 3 for unobstructed use of any particular one of them.

What I claim and desire to secure by Letters Patent of the United States is:—

1. A tuning device comprising a holder and a series of tubes hinged thereto each tube containing a reed.

2. A tuning device comprising a holder, 50 a series of tubes each containing a reed and having a lug at one end, and a pin for rockingly securing each tube to the holder.

3. A tuning device comprising a holder consisting of a strip of material bent into 55 U-shape in cross-section, a series of tubes each containing a reed and having a lug at one end, and a pin passing through said holder and lug to constitute a hinged connection between each tube and the holder.

4. A tuning device comprising a holder consisting of a strip of material bent into U-shape in cross-section and having a series of lugs integrally formed along parallel edges of the holder, a series of tubes each containing a reed and having a lug at one end, and a pin projecting through each opposite pair of lugs on the holder and a lug on one of the tubes to hinge the tube to the holder.

LEOPOLD MULLER.
